UNITED STATES PATENT OFFICE.

WILLIAM H. KIRKWOOD, OF KITTANNING, PENNSYLVANIA.

RAIL CONNECTOR.

1,417,531.

Specification of Letters Patent. Patented May 30, 1922.

Application filed October 29, 1921. Serial No. 511,484.

To all whom it may concern:

Be it known that I, WILLIAM H. KIRKWOOD, a citizen of the United States, residing at Kittanning, in the county of Armstrong and State of Pennsylvania, have invented a new and useful Improvement in Rail Connectors, of which improvement the following is a specification.

My invention relates to improvements in rail joints. The object of the invention is to produce a rail joint which in effect forms a continuous rail, also a rail joint which may be used with efficiency without the use of fish plates.

I accomplish these purposes by means of the device hereinafter specifically described, reference being had to the accompanying drawings forming part hereof, in which—

Fig. 1 is a perspective elevation of my improved rail joint.

Figs. 2 and 3 are respectively side elevations of the interlocking members before assemblage.

Fig. 4 is a bottom plan view.

Fig. 5 is a section on line V—V of Fig. 1. Referring to said drawings; 1, 2 are respectively the adjacent ends of two rails which are respectively provided with interlocking means which include a tapering recess or slot 3 formed in the head of the rail 2 longitudinally thereof, and a correspondingly shaped tongue 4 formed on the head of the adjacent rail 1 and adapted to be inserted within said slot, as shown in the drawings, forming practically a continuous rail. The web of rail 2 is cut away immediately below and on a vertical plane with said slot 3, the remaining portion *a* thereof being provided with a notch 5; the web of said rail 1 being cut away immediately above the flange 6, leaving a portion *b*, which is provided with a prong or member 7, adapted to be inserted in said notch 5, interlocking the ends of said rail as shown in the drawing, the contacting surfaces of the webs being correspondingly inclined and forming, when assembled, a neat joint. The flange 6 of rail 1 is provided with a slot 8, which is substantially equal in length to the tongue 4, the sides of said slot being provided with prongs 9, 10 on opposite sides, the prong 9 being somewhat in advance of

prong 10. The flange 11 of rail 2 is provided with an extension 12 corresponding in shape with said slot 8, and is adapted to be inserted therein and is provided with notches 13 on opposite sides, adapted to receive the prongs 9 and 10, whereby in conjunction with the interlocking members on the head and webs of the rails, as heretofore described, a very efficient interlock is formed between the abutting ends of the rails and forming a continuous joint practically at such point. The rails 1 and 2 may be and are preferably provided with bolt holes 14 to receive bolts 15 for the purpose of fastening fish plates 16, 17 at the joint and for the further purpose of making a very stable and perfect joint at such point.

The manner of assembling the joint is as follows; rail 2 being secured to the ties, rail 1 is slightly elevated above the plane of rail 2 and the end thereof is forced toward the end of rail 2 until the prong 7 is in position to engage in notch 5, section 1 is then dropped and all the interlocking parts engaged and form a substantially continuous rail and rail joint.

Having described my invention, what I claim and desire to secure by Letters Patent is:

In a continuous rail joint the combination of the adjacent ends of two rails provided with interlocking means, which includes a tongue comprising the end portion of the head of one of said rails, the web having a portion cut away on the lower side thereof and a slot formed in the base flange; the head of the adjacent rail having a slot and the web a cut away portion on the upper side and an extension on the base flange, the web of the last mentioned rail having a notch, and the web of the adjacent rail a prong, the projection and prong of one rail being adapted to engage in the corresponding slot or recess on the adjacent rail forming a substantially continuous rail joint.

In testimony whereof, I have hereunto signed my name in the presence of two subscribing witnesses.

WILLIAM H. KIRKWOOD.

In the presence of—

JOHN H. RONEY,
CLARENCE A. WILLIAMS.
